No. 14,603

FEB 5, 1884

UNITED STATES PATENT OFFICE.

HENRY GHEE, OF SYRACUSE, NEW YORK.

DESIGN FOR SPOONS AND TABLE-WARE.

SPECIFICATION forming part of Design No. 14,603, dated February 5, 1884.

Application filed October 12, 1883. Term of patent 14 years.

To all whom it may concern:

Be it known that I, HENRY GHEE, of Syracuse, in the county of Onondaga, in the State of New York, have invented new and useful

5 Improvements in Designs for Spoons and Analogous Table-Ware, of which the following, taken in connection with the accompanying photographic illustration, is a full, clear, and exact description.

10 The design is intended for the usual broad operating end of spoons, knives, and analogous table-ware, said operating end being termed the "bowl" on a spoon, and the "blade" on a knife.

15 The design consists in a group of peculiar indentations in the entire surface of the bowl or blade of the table-ware, causing the same to present a crystalline appearance, as illus-

trated in the annexed photograph, which represents an article of table-ware embodying my 20 design.

What I claim is—

The design for spoons and analogous table-ware, consisting in a group of indentations in the entire surface of the bowl or blade of the 25 article, substantially as described and shown.

In testimony whereof I have hereunto signed my name and affixed my seal, in the presence of two attesting witnesses, at Syracuse, in the county of Onondaga, in the State of New York, 30 this 9th day of October, 1883.

HENRY GHEE. [L. S.]

Witnesses:

FREDERICK H. GIBBS,
C. BENDIXON.
